UNITED STATES PATENT OFFICE.

ALFRED H. HUMPHREY, OF NEW YORK, N. Y.

GAS-LAMP.

No. 892,261.

Specification of Letters Patent.

Patented June 30, 1908.

Application filed May 15, 1907. Serial No. 373,823.

To all whom it may concern:

Be it known that I, ALFRED H. HUMPHREY, a citizen of the United States, residing at the city of New York, county and State of New York, have invented certain new and useful Improvements in Gas-Lamps, of which the following is a specification.

This invention relates to improvements in gas lamps.

The main objects of this invention are, first, to provide an improved gas lamp having inverted burners which is well adapted for use as an outdoor lamp; second, to provide an improved gas lamp having inverted burners in which the burners and the burner valves are effectively protected, and, at the same time, one in which they are easily accessible for purposes of adjustment and the like; and third, to provide an improved gas lamp having inverted burners in which the parts above the burners are so constructed and arranged as to prevent their becoming heated to an undue extent.

Further objects, and objects relating to details of construction, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which,

Figure 1 is a vertical central section through my improved gas lamp, the gas delivery pipe, the casing of the valve therefor, and the burners being shown in full lines; Fig. 2 is an enlarged horizontal section taken on a line corresponding to line 2—2 of Fig. 1; Fig. 3 is an enlarged horizontal section taken on a line corresponding to line 3—3 of Fig. 1; Fig. 4 is an enlarged detail elevation of the globe-supporting band; Fig. 5 is an enlarged plan view of the mantle holder removed from the lamp with a part of the mantles removed; Fig. 6 is an enlarged detail section taken on a line corresponding to line 6—6 of Fig. 5; Fig. 7 is an enlarged detail section taken on a line corresponding to line 7—7 of Fig. 5; Fig. 8 is a detail view showing a modified form of the chimney casing; Fig. 9 is an enlarged, transverse section through the valve casing 6, taken on a line corresponding to the broken line 9—9 of Fig. 1; Fig. 10 is a detail longi-

tudinal section through the valve taken on a line corresponding to the line 10—10 of Fig. 9; and Fig. 11 is an enlarged detail section of the burner showing the structural details of 60 the gas delivery nozzle.

In the drawing, similar numerals of reference refer to similar parts throughout the several views, and the sectional views are taken looking in the direction of the little arrows at the ends of the section lines.

Referring to the drawing, the gas delivery pipe is preferably made up of the supply pipe 1 having a T-coupling on its lower end to which the pipe sections 3 and 4 are connected, 70 the section 4 being a dummy.

At the lower end of the gas delivery pipe is a valve casing 6, which controls the delivery of the gas to the gas delivery ring 5. The valve casing 6 is preferably arranged to project outwardly and downwardly, as clearly appears from the drawing.

The burners, 7,—of which I preferably provide a plurality as illustrated,—are connected to the gas delivery ring 5. The burners are 80 preferably of the Bunsen type, being provided with suitable burner tips, as 8, and valves, as 8'. The burners are arranged through the outwardly-projecting flange 10 at the lower end of the chimney 9 with their 75 tips below and their valves above the same, preferably in an inclined position, as illustrated, the upper ends of the burners being directed outwardly.

The chimney flange is preferably turned 90 upwardly at 11, and is also preferably provided with an annular downwardly-projecting flange 12, within which the burner tips are arranged.

A chimney casing 13, having an outwardly-projecting flange 14 at its lower end, is arranged about the chimney in a spaced relation thereto to form a conduit or passage for air, the chimney casing being open at its upper end, which is preferably arranged so that 100 it is somewhat below the upper end of the chimney. The chimney casing preferably rests on the upturned portion 11 of the chimney flange and is provided with openings 14 through which the burners are arranged. 105 The chimney and chimney casing are preferably connected by means of suitable bolts as 15, the chimney casing being connected to the pipe sections 3 and 4 by means of suitable clips as 15'. The openings 14' in the chimney casing flange are preferably of such size 110 as to permit the flow of air into the chimney

casing about the same, but a satisfactory structure may be produced by providing the air inlet openings for the casing at its edge, as shown in the modified construction of Fig. 8.

- 5 An outer casing 16, having an outwardly and downwardly projecting flange 17 at its lower end, is provided. The outer casing is arranged above the valve casing 6. The flange 17 of the outer casing serves as a support 10 for the shade 18, which is preferably connected thereto by means of the bolts 19. The outer casing is preferably centered and supported by means of the bracket-like projection 20 on the chimney casing. The upper 15 end of the outer casing is open and is preferably protected by the deflector 21, which projects outwardly beyond the same.

The globe 22 is carried by the globe-supporting band 23, which is adapted, when in its closed position, to close against the under side of the flange 17 on the outer casing. The globe-supporting band is adjustably supported, being preferably hinged, so that it may be swung down out of the way when it 25 is desired to secure access to the burners, mantles, or the like, it being shown in its open position by the dotted lines in Fig. 1.

The hinge preferably consists of the outwardly and downwardly-projecting hinge 30 member 27 secured to the valve-casing 6, the outwardly-projecting hinge member 28 on the globe-supporting band, and the pintle 29. By this connection, when the globe-supporting band is open, it swings down and away 35 from the burners, so as to afford free access thereto. The globe-supporting band is preferably held in its closed position by the pin 30, which is adapted to engage over a suitable stop 31 carried by the chimney flange.

40 The globe-supporting band is provided with a double series of perforations as 25 and 26. These series of perforations are separated by the inwardly-projecting flange 24, which is adapted, when the globe-supporting band is 45 in its closed position, to co-act with the flange on the chimney in separating the chamber formed by the globe from the chamber above the flange. When the globe-supporting band is in its closed position, the air passes 50 through the openings 26 therein to the burners, and through the openings 25 to the air ports of the burners, and to the chimney casing, and also there is, under ordinary circumstances, a current of air passing out of 55 the top of the outer casing.

In operation, a current of air is created in the chimney casing, and the air, being drawn in at the bottom thereof, about the burner mixing tubes, very effectively cools the same. 60 In the preferred construction shown in Figs. 1 and 2, the air is effectively directed so that it flows over the entire upper end of the burners. In the modified construction shown in Fig. 8, the same results are secured 65 to a less degree.

Another advantage of the chimney casing is that it forms the air chamber between the chimney and the gas delivery pipe and burner valves, so that the heat radiated from the chimney is largely carried off by the chimney casing. The outer casing, being open at its upper end, also creates an upward draft of air, so that it assists in the cooling of the parts, which, it will be readily understood, is a very great advantage.

70 The mantle supporting plate 32 is preferably supported by a rod 33 adapted to be vertically and revolvably adjusted in the lug 34 through which it is arranged. A suitable button, as 34', is provided on the opposite end of the flange 12 for holding the plate-like mantle holder in its adjusted position. The mantle holder 32 is adapted to fit the flange 12 on the chimney, as clearly appears from Fig. 2. The mantle support is provided with 80 openings 35 adapted to receive the mantle holder rings 38. The mantle holder is provided with upwardly-projecting flanges 36 about the openings 35, and these flanges are notched, as at 37, to receive the arms 39 on 89 the mantle holders 38. The mantles with the mantle holding rings thereon are dropped through the plate from above the same, the arms or lugs 39 being dropped into the notches 37. This effectively holds the mantles in their proper position, centering them and locating the lugs so that the arms or lugs of one mantle do not interfere with those of the adjacent rings. The mantle support 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 of these passages 50 and 51 are preferably provided with valves 53 and 54, respectively, whereby they may be regulated. The passage 51 is controlled by the valve 43, it being provided with a port 47 therefor. This port 47 is so arranged that it is opened and closed on the opening or closing movement of the valve thereby flashing the pilot, the valve being shown in the drawing partially open 10 and in position to flash the pilot. By thus arranging the ports, the gas is supplied to the main burners somewhat before the pilot burner is flashed, and the continued opening movement of the valve cuts off the auxiliary 15 supply of gas to the pilot, the valve 53 for the passage 52 being adjusted to maintain a continuous flame. The pilot 55 is connected to the valve casing at the lower end of the chamber 50, and is arranged through the 20 flange on the chamber as clearly appears in Fig. 1 of the drawing. By arranging the parts in this manner, I provide an effective trap for any sediment, or water, or other material that may be carried down with the gas, 25 which is effectively collected before reaching the burners, and before reaching the valves, so that it cannot clog the ports or passages thereof. I provide the trap chamber with a plug 49, so that the sediment or other matter 30 collected may be drained off. This is of particular advantage on out-of-door lamps, where there is likely to be considerable condensation within the pipes.

It is also of very great advantage to provide 35 a trap for collecting such materials as would be likely to clog the burner nozzles in lamps of this character where the nozzles are inverted, as very small particles, such as pieces of dirt, or rust, or the like are sufficient 40 to clog the nozzles. By this arrangement, such materials passing down the gas delivery pipe are effectively prevented from reaching the nozzles.

To further protect the nozzle 57 from clogging, I provide an inwardly-projecting flange-like lip 58 about the nozzle opening 59. This forms a trap about the nozzle opening into which sediment or the like may be collected. The nozzle is threaded upon the nipple 56, 50 as clearly appears from the drawing.

I have illustrated and described my improved gas lamp in detail in the form preferred by me on account of its structural simplicity and economy. I am, however, aware 55 that it is capable of considerable variation in structural details without departing from my invention, and I desire to be understood as claiming the same specifically, as illustrated, as well as broadly.

Having thus described my invention, what I claim as new and desire to secure by Letters Patent, is:

1. In a gas lamp, the combination with a gas delivery pipe, of a valve casing arranged 65 at the lower end thereof; a gas delivery ring

connected to said gas delivery pipe; a chimney having an outwardly projecting flange at its lower end, the said flange being provided with a downwardly projecting annular flange; the casing for said chimney arranged about the same and spaced therefrom, said chimney being open at its upper end and having an outwardly projecting flange at its lower end, said chimney and casing being arranged through said gas delivery ring 70 connected to said gas delivery pipe; a plurality of inverted burners having valves and burner tips arranged through said flanges on said chimney and chimney casing with their tips below said chimney flange and embraced by 75 the said annular flange thereon, and their valves above the said flange on said chimney casing, said burners being connected to said gas delivery ring; an outer casing open at its upper end and having an outwardly projecting flange at its lower end arranged above 80 said valve casing; a shade carried by said outer casing flange; a deflector arranged above and projecting outwardly beyond the open upper end of said outer casing; a globe 85 supporting band adapted to fit the under side of said outer casing flange when in its closed position, said globe supporting band having a double series of perforations therein; an inwardly projecting flange on said 90 globe supporting band secured thereto between the said series of perforations, said flange being adapted to engage said chimney flange when the globe supporting band is in its closed position; a globe carried by said 95 globe supporting band; an outwardly and downwardly projecting hinge member on said valve casing; and an outwardly projecting hinge member on said globe supporting 100 band pivotally secured thereto, for the purpose specified.

2. In a gas lamp, the combination with a gas delivery pipe, of a valve casing arranged at the lower end thereof; a gas delivery ring connected to said gas delivery pipe; a chimney having an outwardly projecting flange at its lower end, the said flange being provided with a downwardly projecting annular flange; a casing for said chimney arranged about the same and spaced therefrom, said chimney 110 casing being open at its upper end and having an outwardly projecting flange at its lower end, said chimney and casing being arranged through said gas delivery ring connected to said gas delivery pipe; a plurality of inverted burners, having valves and burner tips, arranged through said flanges on said chimney and chimney casing with their tips below said chimney flange and embraced by the said annular flange thereon, and their 115 valves above the said flange on said chimney casing, said burners being connected to said gas delivery ring; an outer casing open at its upper end and having an outwardly projecting flange at its lower end arranged 120

125

above said valve casing; a shade carried by said outer casing flange; a deflector arranged above and projecting outwardly beyond the open upper end of said outer casing; a globe supporting band adapted to fit the under side of said outer casing flange when in its closed position, said globe supporting band having a double series of perforations therein; an inwardly projecting flange on said globe supporting band secured thereto between the said series of perforations, said flange being adapted to engage said chimney flange when the globe supporting band is in its closed position; and a globe supporting band, for the purpose specified.

3. In a gas lamp, the combination with a gas delivery pipe, of a valve casing arranged at the lower end thereof; a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end, said chimney and casing being arranged through said gas delivery ring connected to said gas delivery pipe; a plurality of inverted burners having valves and burner tips, arranged through said flanges on said chimney and chimney casing with their tips below said chimney flange and their valves above the said flange on said chimney casing, said burners being connected to said gas delivery ring; an outer casing open at its upper end and having an outwardly projecting flange at its lower end arranged above said valve casing; a shade carried by said outer casing flange; a deflector arranged above and projecting outwardly beyond the open upper end of said outer casing; a globe supporting band adapted to fit the under side of said outer casing flange when in its closed position, said globe supporting band having a double series of perforations therein; an inwardly projecting flange on said globe supporting band secured thereto between the said series of perforations, said flange being adapted to engage said chimney flange when the globe supporting band is in its closed position; and a globe carried by said globe supporting band, for the purpose specified.

4. In a gas lamp, the combination with a gas delivery pipe, of a valve casing arranged at the lower end thereof; a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end arranged above said valve casing; a globe supporting band adapted to fit the under side of said outer casing flange when in its closed position, said globe supporting band having a double series of perforations therein; an inwardly projecting flange on said globe supporting band secured thereto between the said series of perforations, said flange being adapted to engage said chimney flange when the globe supporting band is in its closed position; a globe carried by said globe supporting band; an outwardly and downwardly projecting hinge member on said valve casing; and an outwardly projecting hinge member on said globe supporting band pivotally secured thereto, for the purpose specified.

5. In a gas lamp, the combination with a gas delivery pipe, of a valve casing arranged at the lower end thereof; a gas delivery ring connected to said gas delivery pipe; a chimney having an outwardly projecting flange at its lower end, the said flange being provided with a downwardly projecting annular flange; a casing for said chimney arranged about the same and spaced therefrom, said chimney casing being open at its upper end and having an outwardly projecting flange at its lower end, said chimney and casing being arranged through said gas delivery ring connected to said gas delivery pipe; a plurality of inverted burners, having valves and burner tips, arranged through said flanges on said chimney and chimney casing with their tips below said chimney flange and embraced by the said annular flange thereon and their valves above the said flange on said chimney casing, said burners being connected to said gas delivery ring; an outer casing having an outwardly projecting flange at its lower end arranged above said valve casing; a globe supporting band adapted to fit the under side of said outer casing flange when in its closed position, said globe supporting band having a double series of perforations therein; an inwardly projecting flange on said globe supporting band secured thereto between the said series of perforations, said flange being adapted to engage said chimney flange when the globe supporting band is in its closed position; and a globe carried by said globe supporting band, for the purpose specified.

6. In a gas lamp, the combination with a gas delivery pipe, of a valve casing arranged at the lower end thereof; a gas delivery ring connected to said gas delivery pipe; a chimney having an outwardly projecting flange at its lower end, the said flange being provided with a downwardly projecting annular flange; a casing for said chimney arranged about the same and spaced therefrom, said chimney casing being open at its upper end and having an outwardly projecting flange at its lower end, said chimney and casing being arranged through said gas delivery ring connected to said gas delivery pipe; a plurality of inverted burners, having valves and burner tips, arranged through said flanges on said chimney and chimney casing with their tips below said chimney flange and embraced by the said annular flange thereon and their valves above the said flange on said chimney casing, said burners being connected to said gas delivery ring; an outer casing having an outwardly projecting flange at its lower end arranged above said valve casing; a globe supporting band adapted to fit the under side of said outer casing flange when in its closed position, said globe supporting band having a double series of perforations therein; an inwardly projecting flange on said globe supporting band secured thereto between the said series of perforations, said flange being adapted to engage said chimney flange when the globe supporting band is in its closed position; a globe carried by said globe supporting band; an outwardly and downwardly projecting hinge member on said valve casing; and an outwardly projecting hinge member on said globe supporting band, for the purpose specified.

supporting band pivotally secured thereto, for the purpose specified.

6. In a gas lamp, the combination with a gas delivery pipe, of a valve casing arranged at the lower end thereof; a gas delivery ring connected to said gas delivery pipe; a chimney having an outwardly projecting flange at its lower end, the said flange being provided with a downwardly projecting annular flange; a casing for said chimney arranged about the same and spaced therefrom; said chimney casing being open at its upper end and having an outwardly projecting flange at its lower end, said chimney and casing being arranged through said gas delivery ring connected to said gas delivery pipe; a plurality of inverted burners having valves and burner tips, arranged through said flanges on said chimney and chimney casing with their tips below said chimney flange and embraced by the said annular flange thereon and their valves above the said flange on said chimney casing, said burners being connected to said gas delivery ring; an outer casing having an outwardly projecting flange at its lower end arranged above said valve casing; a globe supporting band adapted to fit the under side of said outer casing flange when in its closed position, said globe supporting band having a double series of perforations therein; an inwardly projecting flange on said globe supporting band secured thereto between the said series of perforations said flange being adapted to engage said chimney flange when the globe supporting band is in its closed position; and a globe carried by said globe supporting band, for the purpose specified.

7. In a gas lamp, the combination with a gas delivery pipe, of a valve casing arranged at the lower end thereof; a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end, said chimney and casing being arranged through said gas delivery ring connected to said gas delivery pipe; a plurality of inverted burners, having valves and burner tips, arranged through said flanges on said chimney and chimney casing with their tips below said chimney flange and their valves above the said flange on said chimney casing, said burners being connected to said gas delivery ring; an outer casing having an outwardly projecting flange at its lower end arranged above said valve casing; a globe supporting band adapted to fit the under side of said outer casing flange when in its closed position, said globe supporting band having a double series of perforations therein; an inwardly projecting flange on said globe supporting band secured thereto between the said series of perforations.

tions, said flange being adapted to engage said chimney flange when the globe supporting band is in its closed position; a globe carried by said globe supporting band; an outwardly and downwardly projecting hinge member 70 on said valve casing; and an outwardly projecting hinge member on said globe supporting band pivotally secured thereto, for the purpose specified.

8. In a gas lamp, the combination with a 75
gas delivery pipe, of a valve casing arranged
at the lower end thereof; a gas delivery ring
connected to said gas delivery pipe; a chim-
ney having an outwardly projecting flange at
its lower end; a casing for said chimney ar-
ranged about the same and spaced therefrom,
said chimney casing being open at its upper
end and having an outwardly projecting
flange at its lower end, said chimney and cas-
ing being arranged through said gas delivery 80
ring connected to said gas delivery pipe; a
plurality of inverted burners having valves
and burner tips, arranged through said
flanges on said chimney and chimney casing
with their tips below said chimney flange and 85
their valves above the said flange on said
chimney casing, said burners being connect-
ed to said gas delivery ring; an outer casing
having an outwardly projecting flange at its
lower end arranged above said valve casing; 90
a globe supporting band adapted to fit the
under side of said outer casing flange when in
its closed position, said globe supporting
band having a double series of perforations
therein; an inwardly projecting flange on 95
said globe supporting band secured thereto
between the said series of perforations, said
flange being adapted to engage said chimney
flange when the globe supporting band is in
its closed position; and a globe carried by 100
said supporting band, for the purpose
specified.

9. In a gas lamp, the combination with a
gas delivery pipe, of a valve casing arranged
at the lower end thereof; a gas delivery ring 110
connected to said gas delivery pipe; a chim-
ney having an outwardly projecting flange at
its lower end; a casing for said chimney ar-
ranged about the same and spaced therefrom,
said chimney casing being open at its upper 115
end and having an outwardly projecting
flange at its lower end, said chimney and cas-
ing therefor being connected to said gas de-
livery pipe; a plurality of inverted burners
having valves and burner tips arranged 120
through said flanges on said chimney and
chimney casing with their tips below said
chimney flange and their valves above the
said flange on said chimney casing, said
burners being connected to said gas deliv- 125
ery ring; an outer casing open at its upper
end having an outwardly projecting flange
at its lower end arranged above said valve
casing; a shade carried by said outer cas-
ing valve; a deflector arranged above and 130

projecting outwardly beyond the open upper end of said outer casing; a globe supporting band adapted when in its closed position to co-act with said chimney flange; a globe carried by said globe-supporting band; an outwardly and downwardly projecting hinge member on said valve casing; and an outwardly projecting hinge member on said globe supporting band pivotally secured thereto, for the purpose specified.

10. In a gas lamp, the combination with a gas delivery pipe, of a valve casing arranged at the lower end thereof; a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end, said chimney and casing therefor being connected to said gas delivery pipe; a plurality of inverted burners having valves and burner tips arranged through said flanges on said chimney and chimney casing with their tips below said chimney flange and their valves above the said flange on said chimney casing, said burners being connected to said gas delivery ring; an outer casing open at its upper end having an outwardly projecting flange at its lower end arranged above said valve casing; a shade carried by said outer casing valve; a deflector arranged above and projecting outwardly beyond the open upper end of said outer casing; a globe supporting band adapted when in its closed position to co-act with said chimney flange; and a globe carried by said globe supporting band, for the purpose specified.

40 11. In a gas lamp, the combination with a
gas delivery pipe, of a valve casing arranged
at the lower end thereof; a gas delivery ring
connected to said gas delivery pipe; a chim-
ney having an outwardly projecting flange at
45 its lower end; a casing for said chimney ar-
ranged about the same and spaced therefrom,
said chimney casing being open at its upper
end and having an outwardly projecting
flange at its lower end, said chimney and cas-
50 ing therefor being connected to said gas de-
livery pipe; a plurality of inverted burners
having valves and burner tips arranged
through said flanges on said chimney and
chimney casing with their tips below said
55 chimney and their valves above the said
flange on said chimney casing, said burners
being connected to said gas delivery ring; an
outer casing having an outwardly projecting
flange at its lower end arranged above said
60 valve casing; a globe supporting band adapt-
ed when in its closed position to coact with
said chimney flange; a globe carried by said
globe supporting band; an outwardly and
downwardly projecting hinge member on
65 said valve casing; and an outwardly pro-

jecting hinge member on said globe supporting band pivotally secured thereto, for the purpose specified.

12. In a gas lamp, the combination with a gas delivery pipe, of a valve casing arranged at the lower end thereof; a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end, said chimney and casing therefor being connected to said gas delivery pipe; a plurality of inverted burners having valves and burner tips arranged through said flanges on said chimney and chimney casing with their tips below said chimney flange and their valves above the said flange on said chimney casing, said burners being connected to said gas delivery ring; an outer casing having an outwardly projecting flange at its lower end arranged above said valve casing; a globe supporting band adapted when in its closed position to 90 coat with said chimney flange; and a globe carried by said globe supporting band, for the purpose specified. 70 75 80 85 90

13. In a gas lamp, the combination with a gas delivery pipe, of a valve casing arranged at the lower end thereof; a gas delivery ring connected to said gas delivery pipe; a chimney having an outwardly projecting flange at its lower end, arranged through and connected to said gas delivery pipe; a plurality of inverted burners, having valves and burner tips, arranged through said flange on said chimney with their tips below and their valves above the same, said burners being connected to said gas delivery ring; an outer casing open at its upper end and having an outwardly projecting flange at its lower end arranged above said valve casing; a shade carried by said outer casing flange; a deflector arranged above and projecting outwardly beyond the open upper end of said outer casing; a globe supporting band adapted to fit the under side of said outer casing flange when in its closed position, said globe supporting band having a double series of perforations therein; an inwardly projecting flange on said globe supporting band secured thereto between the said series of perforations, said flange being adapted to engage said chimney flange when the globe supporting band is in its closed position; a globe carried by said globe supporting band; an outwardly and downwardly projecting hinge member on said valve casing; and an outwardly projecting hinge member on said globe supporting band pivotally secured thereto, for the purpose specified. 130

14. In a gas lamp, the combination with a gas delivery pipe, of a valve casing arranged at the lower end thereof; a gas delivery ring 130

- connected to said gas delivery pipe; a chimney having an outwardly projecting flange at its lower end, arranged through and connected to said gas delivery pipe; a plurality of inverted burners, having valves and burner tips, arranged through said flange on said chimney with their tips below and their valves above the same, said burners being connected to said gas delivery ring; an outer 5 casing open at its upper end and having an outwardly projecting flange at its lower end arranged above said valve casing; a shade carried by said outer casing flange; a deflector arranged above and projecting outwardly 10 beyond the open upper end of said outer casing; a globe supporting band adapted to fit the under side of said outer casing flange when in its closed position, said globe supporting band having a double series of perforations 15 therein; an inwardly projecting flange on said globe supporting band secured thereto between the said series of perforations said flange being adapted to engage said chimney flange when the globe supporting band is in its closed position; and a globe carried by said globe supporting band, for the purpose specified.
16. In a gas lamp, the combination with a gas delivery pipe, of a valve casing arranged 20 at the lower end thereof; a gas delivery ring connected to said gas delivery pipe; a chimney having an outwardly projecting flange at its lower end, arranged through and connected to said gas delivery pipe; a plurality of burners having valves and burner tips arranged through said flange on said chimney with their tips below and their valves above the same, said burners being connected to said gas delivery ring; an outer casing having 25 an outwardly projecting flange at its lower end arranged above said valve casing; a globe supporting band adapted to fit the under side of said outer casing when in its closed position, said globe supporting band having a double series of perforations 30 therein; an inwardly projecting flange on said globe supporting band secured thereto between the said series of perforations said flange being adapted to engage said chimney flange when the globe supporting band is in its closed position; and a globe carried by said globe supporting band, for the purpose specified.
17. In a gas lamp, the combination with a gas delivery pipe, of a valve casing arranged 35 at the lower end thereof; a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end, said chimney and casing therefor being arranged through said gas delivery ring, connected to said gas delivery pipe; a plurality of inverted burners having valves and burner tips arranged 40 through said flanges on said chimney and chimney casing with their tips below said chimney flange and their valves above the said flange on said chimney casing, said burners being connected to said gas delivery ring; an outer casing having an outwardly projecting flange at its lower end arranged above said valve casing, and a shade carried 45 by said outer casing flange, for the purpose specified.
18. In a gas lamp, the combination with a gas delivery pipe, of a gas delivery ring connected to said gas delivery pipe; a chimney having an outwardly projecting flange at its lower end; a casing for said chimney arranged about the same and spaced therefrom, said chimney casing being open at its upper end and having an outwardly projecting flange at its lower end, said chimney and casing therefor being arranged through said gas delivery ring connected to said gas delivery pipe; and a plurality of inverted 50 burners having valves and burner tips arranged through said flanges on said chimney and chimney casing with their tips below said chimney flange and their valves above the said flange on said chimney casing, said burners being connected to said gas delivery ring, for the purpose specified.
19. In a gas lamp, the combination with a gas delivery pipe, of a chimney having an outwardly projecting flange at its lower end; a casing for said chimney arranged about 55

the same and spaced therefrom, said chimney casing being open at its upper end and having an outwardly projecting flange at its lower end; an inverted burner provided with a valve and a burner tip arranged through said flanges on said chimney and chimney casing with its tip below said chimney flange and its valve above the said flange on said chimney casing; an outer casing having an outwardly projecting flange at its lower end; and a shade carried by said outer casing flange, for the purpose specified.

20. In a gas lamp, the combination with a gas delivery pipe, of a chimney having an outwardly projecting flange at its lower end; a casing for said chimney arranged about the same and spaced therefrom, said chimney casing being open at its upper end and having an outwardly projecting flange at its lower end; an inverted burner provided with a valve and a burner tip arranged through said flanges on said chimney and chimney casing with its tip below said chimney flange and its valve above the said flange on said chimney casing, for the purpose specified.

21. In a gas lamp, the combination with a gas delivery pipe, of a valve casing arranged at the lower end thereof; a chimney having an outwardly projecting flange at its lower end; an inverted burner provided with a valve and a burner tip arranged through said flange on said chimney with its tip below and its valve above the same; an outer casing open at its upper end and having an outwardly projecting flange at its lower end arranged above said valve casing; a shade carried by said outer casing flange; a deflector arranged above and projecting outwardly beyond the open upper end of said outer casing; an adjustably supported globe supporting band adapted to close against the under side of said outer casing flange when in its closed position, said globe supporting band having a double series of perforations therein; an inwardly-projecting flange on said globe supporting band secured thereto between the said series of perforations, said flange being adapted to engage said chimney flange when the globe supporting band is in its closed position; and a globe carried by said globe supporting band, for the purpose specified.

22. In a gas lamp, the combination with a gas delivery pipe, of a valve casing arranged at the lower end thereof; a chimney having an outwardly projecting flange at its lower end; an inverted burner provided with a valve and a burner tip arranged through said flange on said chimney with its tip below and its valve above the same; an outer casing having an outwardly projecting flange at its lower end arranged above said valve casing; a shade carried by said outer casing flange; a deflector arranged above and projecting outwardly beyond the open upper

end of said outer casing; an adjustably supported globe supporting band adapted to close against the under side of said outer casing flange when in its closed position, said globe supporting band having a double series of perforations therein; an inwardly-projecting flange on said globe supporting band secured thereto between the said series of perforations, said flange being adapted to engage said chimney flange when the globe supporting band is in its closed position; and a globe carried by said globe supporting band, for the purpose specified.

23. In a gas lamp, the combination with a gas delivery pipe, of a chimney having an outwardly projecting flange at its lower end; an inverted burner provided with a valve and a burner tip arranged through said flange on said chimney with its tip below and its valve above the same; an outer casing open at its upper end and having an outwardly projecting flange at its lower end; an adjustably supported globe supporting band adapted to close against the under side of said outer casing flange when in its closed position, said globe supporting band having a double series of perforations therein; an inwardly-projecting flange on said globe supporting band secured thereto between the said series of perforations, said flange being adapted to engage said chimney flange when the globe supporting band is in its closed position; and a globe carried by said globe supporting band, for the purpose specified.

24. In a gas lamp, the combination with a gas delivery pipe, of a chimney having an outwardly projecting flange at its lower end; an inverted burner provided with a valve and a burner tip arranged through said flange on said chimney with its tip below and its valve above the same; an outer casing having an outwardly projecting flange at its lower end; an adjustably supported globe supporting band adapted to close against the under side of said outer casing flange when in its closed position, said globe supporting band having a double series of perforations therein; an inwardly-projecting flange on said globe supporting band secured thereto between the said series of perforations, said flange being adapted to engage said chimney flange when the globe supporting band is in its closed position; and a globe carried by said globe supporting band, for the purpose specified.

25. In a gas lamp, the combination with a gas delivery pipe, of a valve casing arranged at the lower end thereof; a chimney having an outwardly projecting flange at its lower end; a casing for said chimney arranged about the same and spaced therefrom, said chimney being open at its upper end and having an outwardly projecting flange at its lower end; an inverted burner provided with a burner tip and a valve arranged

through said flanges on said chimney and chimney casing with its tips below said chimney flange and its valve above the said flange on said chimney casing; an outer 5 casing having an outwardly projecting flange at its lower end arranged above the said valve casing; a shade carried by said outer casing flange; a globe supporting band adapted when in its closed position to coact 10 with said chimney flange; and a globe carried by said globe supporting band, for the purpose specified.

26. In a gas lamp, the combination with a gas delivery pipe, of a chimney having an 15 outwardly projecting flange at its lower end; a casing for said chimney arranged about the same and spaced therefrom, said chimney being open at its upper end and having an outwardly projecting flange at its lower 20 end; an inverted burner provided with a burner tip and a valve arranged through said flanges on said chimney and chimney casing with its tip below said chimney flange and its valve above the said flange on 25 said chimney casing; a globe supporting band adapted when in its closed position to coact with said chimney flange; and a globe carried by said globe supporting band, for the purpose specified.

30 27. In a gas lamp, the combination with a gas delivery pipe, of a valve casing arranged at the lower end thereof; a chimney having an outwardly projecting flange at its lower end; a casing for said chimney arranged 35 about the same and spaced therefrom, said chimney being open at its upper end and having an outwardly projecting flange at its lower end; an inverted burner provided with a burner tip and valve arranged 40 through said flanges on said chimney and chimney casing with its tip below said chimney flange and its valve above the said flange on said chimney casing; an outer 45 casing having an outwardly projecting flange at its lower end arranged above said valve casing; and a shade carried by said outer casing flange, for the purpose specified.

28. In a gas lamp, the combination with a gas delivery pipe, of a chimney having an 50 outwardly projecting flange at its lower end; a casing for said chimney arranged about the same and spaced therefrom, said chimney being open at its upper end and having an outwardly projecting flange at its lower end; 55 and an inverted burner provided with a burner tip and a valve arranged through said flanges on said chimney and chimney casing with its tip below said chimney flange and its valve above the said flange on said chimney casing.

60 29. In a gas lamp, the combination with a gas delivery pipe, of a valve casing arranged at the lower end thereof; a chimney having an outwardly projecting flange at its lower 65 end; an inverted burner, provided with a

valve and a burner tip, arranged through said flange on said chimney with its tip below and its valve above the same; an outer casing having an outwardly projecting flange at its lower end arranged above said valve 70 casing; a shade carried by said outer casing flange; an adjustably supported globe supporting band adapted to coact with said flange on said chimney when in its closed position; and a globe carried by said globe supporting band, for the purpose specified. 75

30. In a gas lamp, the combination with a gas delivery pipe, of a chimney having an outwardly projecting flange at its lower end; an inverted burner, provided with a valve and a 80 burner tip, arranged through said flange on said chimney with its tip below and its valve above the same; an outer casing; an adjustably supported globe supporting band adapted to coact with said flange on said chimney 85 when in its closed position; and a globe carried by said globe supporting band, for the purpose specified.

31. In a gas lamp, the combination of a gas delivery pipe; a valve casing at the 90 lower end thereof; a chimney supported by said gas delivery pipe, said chimney having an outwardly projecting flange at its lower end; an inverted burner, having a burner provided with a tip and a valve, arranged 95 through said chimney flange with its valve above and its tip below the same; an outer casing arranged above said valve casing; a globe; a globe-supporting band; a hinge for said globe-supporting band comprising a 100 downwardly projecting hinge member carried by said valve casing; and an outwardly projecting hinge member on said globe supporting band; and a pivot for said hinge members. 105

32. In a gas lamp, the combination of a gas delivery pipe; a valve casing at the lower end thereof; a chimney supported by said gas delivery pipe, said chimney having an outwardly projecting flange at its lower end; 110 an inverted burner provided with a tip and a valve arranged through said chimney flange with its valve above and its tip below the same; an outer casing arranged above said valve casing; a globe; a globe supporting 115 band; and a pivotal connection for said globe-supporting band to said valve casing.

33. In a gas lamp, the combination of a gas delivery pipe; a chimney having an outwardly-projecting flange at its lower end connected thereto; a gas delivery ring through which said chimney is arranged connected to said gas delivery pipe; a plurality of inverted burners with separate mantles therefor grouped about said chimney and connected 120 to said gas delivery ring, said burners being arranged through the flange of said chimney; a casing opening at its upper end arranged to embrace said gas delivery ring and the upper ends of said burners; a globe arranged to em- 125 130

brace said burner mantles; and a partition separating the chamber formed by said globe from the lower end of said casing, said casing being provided with air inlet openings at the 5 lower end thereof.

34. In a gas lamp, the combination with a gas delivery pipe, of a valve casing arranged at the lower end thereof; a chimney having an outwardly-projecting flange at its lower 10 end; an inverted burner arranged through said flange of said chimney; an outer casing having an outwardly-projecting flange arranged above said valve casing; a shade carried by said flange on said outer casing; a 15 globe supporting band, and a globe carried thereby arranged below said valve casing.

35. In a gas lamp, the combination of a gas delivery pipe; a chimney having an outwardly projecting flange at its lower end; a 20 chimney casing open at its ends arranged about said chimney in a spaced relation thereto; a plurality of inverted burners provided with burner tips and valves grouped about said chimney and connected to said 25 gas delivery pipe, said burners being arranged through said flange of said chimney with their tips below and their valves above the same, and on the outside of said chimney casing; an outer casing; a globe inclosing said 30 burner tips; and a partition for separating said chamber formed by said globe from the chamber formed by said outer casing, said outer casing being open at its upper end and being provided with air inlet openings at the 35 lower end thereof.

36. In a gas lamp, the combination with a gas delivery pipe, of a valve casing arranged at the lower end thereof; a chimney having an outwardly projecting flange at its lower 40 end; an inverted burner arranged through said flange on said chimney; an outer casing; a shade carried by said outer casing, and a globe arranged below said valve casing.

37. In a gas lamp, the combination of a 45 gas delivery pipe; a chimney; a plurality of inverted burners comprising burner tips and tubes grouped about said chimney; and a chimney casing arranged about said chimney in a spaced relation thereto and between said 50 chimney and said burner tubes, said chimney casing being open at its upper and lower ends, for the purpose specified.

38. In a gas lamp, the combination with the gas delivery pipe, of a gas delivery ring 55 connected to said gas delivery pipe; a chimney having an outwardly-projecting flange at its lower end arranged through said gas delivery ring; a casing for said chimney arranged about the same and spaced therefrom, said chimney casing being open at its upper 60 end and having an outwardly-projecting flange at its lower end arranged to rest on said flange on said chimney; a plurality of inverted burners provided with tips and valves grouped about said chimney casing and connected to said gas delivery ring, said burners being arranged through the flanges on said chimney and chimney casing, said chimney casing flange being provided with openings 65 through which said burners are arranged, the openings being of such diameter as to form an air passage about the burners; an outer casing open at its upper end; a globe-supporting band below said outer casing, adapted to 130

and connected to said gas delivery ring, said burners being arranged in an inclined position through the flanges on said chimney and chimney casing, the upper ends of the burners being directed outwardly, said chimney 70 casing flange being provided with openings through which said burners are arranged, the openings being of such diameter as to form an air passage about the burners; an outer casing open at its upper end; a globe supporting band below said outer casing, adapted to 75 coact therewith to inclose the upper ends of the burners, said globe supporting band having a double series of perforations therein, the upper series being located adjacent to the upper ends of said burners; and an inwardly-projecting flange on said globe- 80 supporting band arranged between the said series of perforations and adapted to engage said chimney flange. 85

39. In a gas lamp, the combination with the gas delivery pipe, on a gas delivery ring connected to said gas delivery pipe; a chimney having an outwardly-projecting flange at its lower end arranged through said gas 90 delivery ring; a casing for said chimney arranged about the same and spaced therefrom, said chimney casing being open at its upper end and having an outwardly-projecting flange at its lower end arranged to rest on said flange on said chimney; a plurality of inverted burners provided with tips and valves grouped about said chimney casing and connected to said gas delivery ring, said 95 burners being arranged in an inclined position through the flanges on said chimney and chimney casing, the upper ends of the burners being directed outwardly, said chimney casing flange being provided with openings through which said burners are arranged, the openings being of such diameter as to form an air 100 passage about the burners. 105

40. In a gas lamp, the combination with the gas delivery pipe, of a gas delivery ring 110 connected to said gas delivery pipe; a chimney having an outwardly-projecting flange at its lower end arranged through said gas delivery ring; a casing for said chimney arranged about the same and spaced therefrom, said chimney casing being open at its upper 115 end and having an outwardly-projecting flange at its lower end arranged to rest on said flange on said chimney; a plurality of inverted burners provided with tips and valves grouped about said chimney casing and connected to said gas delivery ring, said burners being arranged through the flanges on said chimney and chimney casing, said chimney casing flange being provided with openings 120 through which said burners are arranged, the openings being of such diameter as to form an air passage about the burners; an outer casing open at its upper end; a globe-supporting band below said outer casing, adapted to 125 coact therewith to inclose the upper ends of 130

the burners, said globe-supporting band having a double series of perforations therein, the upper series being located adjacent to the upper ends of said burners; and an inwardly-projecting flange on said globe-supporting band arranged between the said series of perforations and adapted to engage said chimney flange.

41. In a gas lamp, the combination with the gas delivery pipe, of a gas delivery ring connected to said gas delivery pipe; a chimney having an outwardly-projecting flange at its lower end arranged through said gas delivery ring; a casing for said chimney arranged about the same and spaced therefrom, said chimney casing being open at its upper end and having an outwardly-projecting flange at its lower end arranged to rest on said flange on said chimney; a plurality of inverted burners provided with tips and valves grouped about said chimney casing and connected to said gas delivery ring, said burners being arranged through the flanges on said chimney and chimney casing, said chimney casing flange being provided with openings through which said burners are arranged, the openings being of such diameter as to form an air passage about the burners.

42. In a gas lamp, the combination with the gas delivery pipe, of a chimney having an outwardly-projecting flange at the lower end; a casing for said chimney arranged about the same and spaced therefrom, said chimney casing being open at its upper end and having an outwardly-projecting flange at its lower end arranged to rest on said chimney; a plurality of inverted burners provided with tips and valves grouped about said chimney casing and connected to said gas delivery ring, said burners being arranged in an inclined position through the flanges on said chimney and chimney casing, the upper ends of the burners being directed outwardly, said chimney casing flange being provided with openings through which said burners are arranged, the diameters of said openings exceeding that of the burners; an outer casing open at its upper end; a globe-supporting band below said outer casing, adapted to coact therewith to inclose the upper ends of the burners, said globe-supporting band having a double series of perforations therein, the upper series being located adjacent to the upper ends of said burners; and an inwardly-projecting flange on said globe-supporting band arranged between said series of perforations and adapted to engage said chimney flange.

43. In a gas lamp, the combination with the gas delivery pipe, of a chimney having an outwardly-projecting flange at the lower end; a casing for said chimney arranged about the same and spaced therefrom, said chimney casing being open at its upper end and having an outwardly-projecting flange at its lower end arranged to rest on said chimney;

a plurality of inverted burners provided with tips and valves grouped about said chimney casing and connected to said gas delivery ring, said burners being arranged in an inclined position through the flanges on said chimney and chimney casing, the upper ends of the burners being directed outwardly, said chimney casing flange being provided with openings through which said burners are arranged, the diameters of said openings appreciably exceeding that of the burners.

44. In a gas lamp, the combination with the gas delivery pipe, of a chimney having an outwardly-projecting flange at the lower end; a casing for said chimney arranged about the same and spaced therefrom, said chimney casing being open at its upper end and having an outwardly-projecting flange at its lower end arranged to rest on said chimney; a plurality of inverted burners provided with tips and valves grouped about said chimney casing and connected to said gas delivery ring, said burners being arranged through the flanges on said chimney and chimney casing, said chimney casing flange being provided with openings through which said burners are arranged, the diameters of said openings appreciably exceeding that of the burners; an outer casing open at its upper end; a globe-supporting band below said outer casing, adapted to coact therewith to inclose the upper ends of the burners, said globe-supporting band having a double series of perforations therein, the upper series being located adjacent to the upper ends of said burners; and an inwardly-projecting flange on said globe-supporting band arranged between said series of perforations and adapted to engage said chimney flange.

45. In a gas lamp, the combination with the gas delivery pipe, of a chimney having an outwardly-projecting flange at the lower end; a casing for said chimney arranged about the same and spaced therefrom, said chimney casing being open at its upper end and having an outwardly-projecting flange at its lower end arranged to rest on said chimney; a plurality of inverted burners provided with tips and valves grouped about said chimney casing and connected to said gas delivery ring, said burners being arranged through the flanges on said chimney and chimney casing, said chimney casing flange being provided with openings through which said burners are arranged, the diameters of said openings appreciably exceeding that of the burners.

46. In a gas lamp, the combination with a gas delivery pipe, of a chimney having an outwardly-projecting flange at its lower end; a casing for said chimney having an outwardly-projecting flange at its lower end; an inverted burner provided with a tip at its lower end and valves at its upper end and arranged through said chimney and chimney

casing flange in an inclined position with its upper end directed outwardly, the diameter of the opening in said chimney casing flange through which said burner is arranged being 5 of such size as to permit the passage of air about the same; and an outer inclosure for said burner having air inlets adjacent to the upper ends thereof.

47. In a gas lamp, the combination with a 10 gas delivery pipe, of a chimney having an outwardly-projecting flange at its lower end; a casing for said chimney having an outwardly-projecting flange at its lower end; an inverted burner provided with a tip at its 15 lower end and valves at its upper end and arranged through said chimney and chimney casing flanges in an inclined position with its upper end directed outwardly, the diameter of the opening in said chimney casing flange 20 through which said burner is arranged being of such size as to permit the passage of air about the same; and an outer inclosure for said burner.

48. In a gas lamp, the combination with a 25 gas delivery pipe, of a burner; a chimney; a valve casing arranged at the lower end of said gas delivery pipe on the outside of said chimney; an outer casing arranged about said chimney above said valve casing; a shade carried by said outer casing; and a globe arranged below said valve casing.

49. In a gas lamp, the combination with a 35 gas delivery pipe of a burner; a chimney; a valve casing arranged at the lower end of said gas delivery pipe on the outside of said chimney; and an outer casing arranged about said chimney, said outer casing having an outwardly-projecting flange at its lower end arranged to project over said valve casing.

50. In a gas lamp, the combination with a 40 gas delivery pipe, of a chimney; a burner comprising a burner tip and tube arranged in an inverted position; and a chimney casing arranged about said chimney in a spaced relation thereto and between said casing and the burner tube, said casing being open at its upper and lower ends to permit the circulation of air therethrough, for the purpose specified.

51. In a gas lamp, the combination with a 45 gas delivery pipe of a burner; a chimney; an outer casing having an outwardly-projecting flange at its lower end; an inclosing globe for said burner; a globe-supporting band therefor having air-inlets therein, the said flange of said outer casing projecting over said globe-supporting band, whereby said air-inlets in said globe-supporting band are protected.

52. In a gas lamp, the combination with a

gas delivery pipe of a burner; a chimney; an outer casing having an outwardly-projecting flange at its lower end; an inclosing globe for said burner, there being air-inlet openings for said burner above said globe, said flange of 65 said outer casing being arranged to project over said air-inlet openings, whereby the same are protected.

53. The combination with a gas delivery pipe, of a burner; a pilot burner; a valve casing provided with a trap chamber connected to said gas delivery pipe, a valve chamber to which said burner is connected located above said trap chamber and connected thereto by a suitable passage, and a pilot burner chamber 70 to which said pilot burner is connected, connected to said drain and valve chambers by suitable passages; valves for regulating said connecting passages for said pilot burner chamber to said trap and valve chambers; a 75 hollow plug valve adapted to control said connecting passage for said trap chamber and valve chamber and having a port therein adapted, on the opening movement thereof, to be brought into and out of registry with 80 said port connecting said pilot burner chamber and valve chamber; and a drain plug for said trap chamber.

54. The combination with a gas delivery pipe, of a burner; a pilot burner; a valve casing provided with a trap chamber connected to said gas delivery pipe, a valve chamber to which said burner is connected located above said trap chamber and connected thereto by a suitable passage, and a pilot burner chamber 90 to which said pilot burner is connected, connected to said drain and valve chambers by suitable passages; a hollow plug valve adapted to control said connecting passage 95 for said trap chamber and valve chamber and having a port therein adapted, on the opening movement thereof, to be brought into and out of registry with said port connecting said pilot burner chamber and valve chamber; and a drain plug for said trap chamber. 100

55. The combination with a gas delivery pipe, of a burner; a valve casing provided with a trap chamber to which said gas delivery pipe is connected to deliver and a valve 110 chamber to which said burner is connected located above said trap chamber and connected thereto by a suitable passage; and a drain plug for said trap chamber. 115

In witness whereof, I have hereunto set my hand and seal in the presence of two witnesses.

ALFRED H. HUMPHREY. [L. s.]
